(57) **CLAIM**

I claim, the ornamental design for a random linear paving slab, as shown and described.

DESCRIPTION

FIG. 1 shows a front perspective view of a paver according to a first exemplary embodiment of the present disclosure; FIG. 2 shows a front elevation view of the paver illustrated in FIG. 1;

FIG. 3 shows a rear elevation view of the paver illustrated in FIG. 1;

FIG. 4 shows a right side view of the paver illustrated in FIG. 1;

FIG. 5 shows a left side view of the paver illustrated in FIG. 1;

FIG. 6 shows a top view of the paver illustrated in FIG. 1; FIG. 7 shows a bottom view of the paver illustrated in FIG. 1; and,

FIG. 8 shows an environmental view of the paver illustrated in FIG. 1.

The dashed broken lines are for illustrative purposes only and form no part of the claimed design.
